DESIGN FOR PRINTING TYPE FONT

Imre Reiner, Lugano, Switzerland, assignor to Bauer Type Foundry, Inc., New York, N. Y., a corporation of New York

Application November 25, 1935, Serial No. 59,732

Term of patent 7 years

To all whom it may concern:

Be it known that I, Imre Reiner, a citizen of the Kingdom of Hungary, residing at Lugano, Switzerland, have invented a new, original, and ornamental Design for Printing Type Font, of which the following is a specification, reference being had to the accompanying drawing, forming in part thereof,

The figure of the drawing is a plan view of the upper and lower type cases of the font constituting my design.

I claim:

The ornamental design for printing type font as shown.

IMRE REINER.
